L. H. BRINKMAN.
METHOD AND APPARATUS FOR DRAWING METAL.
APPLICATION FILED FEB. 10, 1919.

1,329,455.

Patented Feb. 3, 1920.

UNITED STATES PATENT OFFICE.

LOUIS H. BRINKMAN, OF GLEN RIDGE, NEW JERSEY, ASSIGNOR TO BALL ROLLED TUBE CORPORATION, A CORPORATION OF NEW YORK.

METHOD AND APPARATUS FOR DRAWING METAL.

1,329,455.

Specification of Letters Patent.

Patented Feb. 3, 1920.

Application filed February 10, 1919. Serial No. 275,939.

To all whom it may concern:

Be it known that I, LOUIS H. BRINKMAN, a citizen of the United States, residing at Glen Ridge, county of Essex, and State of New Jersey, have invented new and useful Improvements in Methods and Apparatus for Drawing Metal, of which the following is a specification.

This invention relates to the drawing of metal rods or tubes.

Where the metal to be drawn is heated in a furnace, particularly where the furnace is heated by an oil or gas flame, if the furnace gases flow into contact with the metal too intense heating of the metal may occur or the heating of the metal may be unevenly distributed or both. This is notably the case in connection with the drawing of thin tubes. Also where the furnace gases, especially where the furnace is heated by gas or oil flames, are projected against the metal, it is liable to oxidize and form scale, which is most objectionable in the case of thin tubes.

It is one object of the invention to shield the metal to be drawn from becoming excessively heated.

It is a further object of the invention to evenly distribute the heating of the metal.

It is a further object of the invention to prevent the formation of scale.

Other and ancillary objects of the invention will appear hereinafter.

While the invention will probably prove most useful when employed in a furnace, it may have other applications.

In the accompanying drawing which illustrates the invention—

The figure is a view partly in side elevation and partly in section of an apparatus embodying the invention and illustrating means whereby the method may be carried out.

Referring to the drawings, 1 is a suitable furnace, which may be heated by an oil flame, fuel or fuel and air being admitted to the interior of the furnace by suitable pipes or nozzles 2 and 3.

Extending through the furnace is a heat distributing and metal shielding tube 4 of metal having suitable heat capacity.

Extending through the tube 4 is a tube 5

to be drawn through the die 6 having a series of balls 7, arranged circumferentially of the tube 5 and constituting the members of the die which operate upon the work. The ring 8 circumscribing the balls 7 is rotated by an electric motor 9 and suitable cooling means may be provided for the die parts. It is unnecessary herein, however, to describe in further detail the structure of the die or the arrangement of it in conjunction with the motor as such an apparatus is shown and described in my Patent No. 1,203,306, issued October 31st, 1916, and particularly with reference to Figs. 1 to 8 thereof, this showing including a draw bench for drawing the tube through the die which may be used in the apparatus of the present case. Within the tube extends a mandrel comprising the tube 10 extending through the furnace and having secured at its end a high speed steel head 11 lying under the balls 7 and between which and the balls the tube is reduced. The head 11 is secured to the tube 10 by means of a member 12, having on the one end a screw threaded nipple 13 screwed into the end of the tube and on the other end a screw threaded nipple 14, screwed into the head 11. The member 12 is provided with a shoulder 15 which spaces the head 11 away from the member 12 by a space 16, thus retarding the communication of heat from the head to the member 12. The member 12 is of iron or steel of a less refractory character than that of the head 11 and at the high temperatures at which it is possible to work the head 11, the threads in the member 12 whereby the head 11 is secured, would be liable to soften and strip off. Accordingly means is provided for cooling the member 12 and particularly the nipple 14 so that its threads will not become sufficiently heated to be distorted, care being taken to prevent the cooling fluid from being dashed against the head 11. To this end the member 12 is provided with a central passage 17 which, it will be observed, does not extend entirely through the member 12 to the head, but is separated from the head by a partition 18. Directly opposite the mouth of the passage 17 is the end of a pipe 19 which, at its other end is connected with a suitable source of cooling water under

suitable pressure. As the water is ejected under pressure from the end of the pipe 19, it is projected into the passage 17 and operates to cool the member 12 and the nipple 5 by which it is connected to the head 11 as has been before referred to. All of the water which is expelled from the pipe 19, flows back through the tube 10 of the mandrel, thereby cooling the same and is drained 10 out of the opening 20.

To protect the tube 10 which would not ordinarily be of highly refractory material, from undue heating in the furnace, it is surrounded by a suitable heat insulating covering 21. This may be of asbestos which may be maintained in position by means of an enclosing metal sleeve 22. Inasmuch as the function of the sleeve 22 is simply to hold the heat insulation in place, it may soften to 15 a considerable extent without affecting the operation of the apparatus and consequently is not necessary to be absolutely refractory at the temperature to which it is subjected within the furnace.

25 It will be seen that the tube 4 extends beyond the furnace and practically fills the gap between the furnace and the die so that the heat of the tube to be drawn is preserved in its passage from the furnace to the die so 30 that it is delivered to the latter at the proper drawing temperature. Otherwise the tube might become unduly cooled, particularly if it is thin.

To draw a tube, the mandrel is withdrawn 35 from the rear end of the furnace. A tube to be drawn is entered within the tube 4 which may then be heated up or may have previously been heated. The tube 4 imparts its heat to the tube 5 and when at the proper 40 temperature the latter is passed through the die. It being understood that the mandrel is inserted with its head under the balls as shown in the drawing and the end of the tube secured to the draw head as described 45 in my patent above referred to. The drawing of the tube over the mandrel head beneath the balls effects the desired reduction. After the length of tube has been drawn through the die, the mandrel may be withdrawn 50 from the rear of the furnace, a new length of tube inserted, heated and drawn as described, and this operation repeated indefinitely.

It will be seen that the tube 4 shields the 55 metal to be drawn from the gases of the furnace so that the formation of scale is mitigated or prevented. Also the hot gases do not beat against the metal so that danger of excessive heating, especially of thin tubes, is 60 prevented. Further the conductivity of the metal of the tube 4 causes any heat received to tend to distribute itself through the tube so that the heat imparted to the metal to be drawn is more evenly distributed. Also this 65 conductivity causes heat to be conveyed to

that portion of the tube 4 between the furnace and the die so that the tube to be drawn has its heat maintained so that it is delivered to the die under the proper heat conditions.

70 While the invention of apparatus has been illustrated in what is considered its best embodiment and the method has been recited in detail in connection with an apparatus by which it may be carried out, it is to be understood that neither the invention of apparatus or method is limited to the apparatus of the drawings, nor is the method limited to the precise details recited.

75 What I claim is—

1. The method of drawing metal, which consists in causing it to acquire the desired heat from heated walls between which it is passed, and passing it through a reducing 80 pass.

2. The method of drawing metal, which consists in causing it to acquire the desired heat from a heated tube through which it is passed, and passing it through a reducing 85 pass.

3. The method of drawing metal, which consists in causing it to acquire the desired heat from heated walls between which it is passed, the said walls being heated simultaneously with the passage of the metal, 90 and passing the metal through a reducing pass.

4. The method of drawing metal, which consists in imparting to it the desired heat from a tube through which the metal is 100 passed, said tube being heated from the exterior simultaneously with the passage of said metal and passing the metal through a reducing pass.

5. The method of drawing metal, which 105 consists in imparting heat to said metal from hot gases, while shielding it from said gases and passing the metal through a reducing pass.

6. The method of drawing metal, which 110 consists in heating a heat conducting wall by hot gases, and heating metal to be drawn by imparting heat from said wall to said metal, whereby the heat imparted to said metal is more uniformly distributed, and passing 115 the heated metal through a reducing pass.

7. In metal drawing apparatus, the combination with walls between which the metal is passed, and wherein it is heated to the desired degree by heat derived from said walls, 120 means for heating said walls and a pass for reducing the heated metal.

8. In metal drawing apparatus, the combination with a tube through which the metal is passed, and wherein it is heated to the desired degree by heat derived from said tube, 125 means for heating said tube and a pass for reducing the heated metal.

9. In metal drawing apparatus, the combination with a furnace of a tube in said 130

furnace through which the metal is adapted to be passed and a pass for reducing the metal.

10. In metal drawing apparatus, the combination with a furnace of a tube extending entirely through said furnace, through which the metal is adapted to be passed and a pass for reducing the metal.

11. In metal drawing apparatus, the com-

bination with a furnace of a tube in said furnace through which the metal is adapted to be passed, and a pass for reducing the metal, said tube extending outside the furnace into the space between said furnace and pass.

In testimony whereof I have signed this specification this 31st day of January, 1919.

LOUIS H. BRINKMAN.
